UNITED STATES PATENT OFFICE.

JOHN P. LYBARGER, OF VAN WERT, ASSIGNOR TO JOHN R. ASHTON, OF LIMA, OHIO.

AUTOMATIC ELEVATOR.

SPECIFICATION forming part of Letters Patent No. 507,712, dated October 31, 1893.

Application filed September 13, 1892. Serial No. 445,794. (No model.)

To all whom it may concern:

Be it known that I, JOHN P. LYBARGER, a citizen of the United States, residing at Van Wert, in the county of Van Wert and State of Ohio, have invented certain new and useful Improvements in Automatic Elevators; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to hoisting apparatus for mines, quarries and other places where dirt, broken stone or ore, metal or other like material is carried from one level to a higher, and is designed to furnish a simple and efficient means by which that part of the cars carrying such material may be separated from their carrying trucks and raised with their loads and emptied automatically without the necessity of an attendant at the upper end of 25 the shaft, and then returned into position to receive their loads at the bottom of the shaft.

It consists mainly in providing an elevator cage or platform open on two sides with the bottom so constructed as to straddle the rail 30 on which the car runs in the bottom of the shaft, and provided with guiding and controlling ways by means of which the elevator car proper is retained in position while the cage is rising to the upper level, and so constructing the ways that the car body will be caused to dump when the platform reaches its highest point and will be automatically returned to a position to receive loads as the car starts on its descent, and in other minor 35 details of construction which will be hereinafter more fully described with reference to the accompanying drawings.

In the drawings,—Figure 1 is a side elevation showing my improvement with the car 45 at its highest point ready to dump or discharge. Fig. 2 is a similar view with the car at its lowest point to receive a load. Fig. 3 is a front elevation partly in section of the car and connections at the bottom of the frame 50 or at its lowest position. Fig. 4 is a plan view partly in section of the car, cage or plat-

form and carrying devices. Figs. 5 and 6 are detail views of the dumping yoke.

Referring to the drawings,—A represents the elevator proper consisting of an open cage 55 or frame having corner posts *a a*, carrying rollers *a'*, bearing against the uprights *b*, of the guiding frame B, which is suitably braced by cross pieces *b'*. The elevator cage is connected at its upper end with a hoisting rope, as 60 usual. Inside the elevator cage is mounted a yoke C (see Figs. 1 and 3), consisting of a cross-bar C', and two uprights C² C², horizontal side piece C³, carried upon rollers *c*, mounted upon tracks *c'*, fastened to the side pieces of the cage. 65 This yoke has a sidewise movement transversely in the cage, such movement being controlled by guides F F mounted in the frame B. The yoke carries at a point forward of its center, open bearings D on either side, the 70 object of which is to provide rests for the pivot of the car body to be elevated. At the rear end of the yoke are horizontal rests D' to retain it in a horizontal position while the cage is being elevated. The guides F F mounted 75 in the frame are vertical from the lower end of the shaft until they reach a point near the dumping position where they are inclined forward at an angle of about forty-five degrees, as shown, and then carried upward. To the 80 front standards of the cage are journaled on each side, rollers G G, to sustain the forward end of the car body until such time as the car is ready to dump. To the rear standards of the cage, and fastened to a cross-bar running 85 from one to the other, is secured a spring or springs M bearing on the upper side of the rear end of the car body in its upper position, the object of which is to return the car to a horizontal position when the load is emptied 90 from it.

In operation the cage is lowered to the bottom of the shaft until the lower portions of the yoke comprising the side pieces C³ having the open bearings D, are somewhat below the 95 level of the track on which the cars run at the bottom of the shaft, this position of the parts being more clearly seen in Figs. 2 and 3. The car is then pushed into the cage between the uprights C² of the yoke, the car body H being, 100 by preference, separable from the running gear H' and having at its center a cross bar

or trunnion *J* the ends *j* of which are rounded and project from the opposite sides thereof as clearly seen in Fig. 3. To the forward end of the car on each side is also secured a plate 5 *K*. The trunnions *j*, are in such position on the car body *H*, that when the car has been pushed into the cage to the position indicated in Figs. 2 and 3, they will lie directly above and in line with the open bearings *D*, 10 on the side pieces *C*³ of the yoke, and the plates *K* are likewise so placed on the sides of the car body as to lie in the same vertical plane with rollers *G* secured to the inner faces of the uprights *A'* of the frame of the cage. 15 Thus it will be seen that as the cage is elevated from the position seen in Figs. 2 and 3, the open bearings *D* and rollers *G* on the yoke and uprights will take under, respectively, the trunnions *j* and plates *K* on the car body 20 *H*, and that the horizontal rests *D'* will likewise take under and support the rear end of the car body *H*, whereby said car body is lifted off its running gear and carried upward in the shaft with the elevator cage. As the 25 car body *H* is held securely on the side pieces *C*³, of the yoke with the open bearings *D* on which its trunnions *j* engage, and as this said yoke is guided in its upward and downward movement by the vertical guide ways *F*, *F*, 30 with which the rollers *L* on the uprights *C*² engage, it is evident that the car body *H* will be held in the same position in the cage until the rollers *L* reach the angular portion *F'* of guides *F* when the yoke bearing the 35 car body *H* with it, will be forced sidewise in the elevator cage assuming the position seen in Fig. 1. The length of the plates *K*, on the car body *H* is such that when the yoke has been pushed sidewise by the angular portion 40 *F'*, of the guides *F*, said plates will pass the rollers *G*, on the uprights of the elevator cage, allowing the forward end of the car body *H* to fall as seen in Fig. 1 whereby the said car body turns upon the trunnions *j*, raising its 45 rear end off the rests *D'*, compressing springs *M*, and dumping its contents forward into a suitably arranged chute, as seen in Fig. 1. After the dumping has been effected, the tension of the spring or springs *M*, upon the rear 50 end of the car body *H*, returns the same to its normal horizontal position, and as the machinery of the hoisting apparatus is reversed, to lower the cage in the shaft, the angular portions *F'* of guides *F* act in the reverse man-

ner drawing the car body *H*, into the cage, 55 and lowering it down again onto its running gear *H'* which had been left in position to receive it at the bottom of the shaft as will be understood.

Having thus described my invention, what 60 I claim is—

1. In a hoisting apparatus, the combination with a cage, of a yoke movably mounted therein and adapted to carry the car body, a support on the cage for upholding one end 65 of said car body, and means for moving said yoke laterally in the cage whereby the car body is withdrawn from engagement with its support, substantially as set forth.

2. In a hoisting apparatus, the combination 70 of a cage open at the bottom and ends, a yoke adapted to travel on a track in the cage, bearings carried by the yoke for sustaining a car body and plates and rollers adapted to hold the car body in a horizontal position and 75 guides adapted to act on the yoke to push it forward and thereby release the plates from the rollers and dump the car.

3. In a hoisting apparatus, the combination 80 with a cage, of a yoke movably mounted therein, said yoke being provided with bearings adapted to receive trunnions mounted on the car body, guides adapted to move the yoke laterally in the cage, means liberated by the movement of the yoke for holding said car 85 body in a horizontal position and means for returning said car body to a horizontal position after the load is dumped, substantially as set forth.

4. In a hoisting apparatus, the combination 90 with a cage, of a yoke movably mounted therein, said yoke being provided with open bearings adapted to take under the trunnions of the car body, rests mounted on said yoke behind said bearings and adapted to support 95 the rear end of the car body, rollers on the cage adapted to engage projections on the car body, guides for moving the yoke laterally in the cage and springs mounted on the cage and adapted to return the car body to its 100 horizontal position, substantially as set forth.

In testimony whereof I affix my signature in presence of two witnesses.

JOHN P. LYBARGER.
